UNITED STATES PATENT OFFICE.

JOHN L. DAWES, OF PITTSBURGH, PENNSYLVANIA.

PROTECTOR FOR LAMPS OR SIGN STRUCTURES.

1,305,696.

Specification of Letters Patent. Patented June 3, 1919.

Application filed January 9, 1919. Serial No. 270,293.

To all whom it may concern:

Be it known that I, JOHN L. DAWES, a citizen of the United States, residing at Pittsburgh, county of Allegheny, and State 5 of Pennsylvania, have invented a new and useful Improvement in Protectors for Lamps or Sign Structures, of which the following is a full, clear, and exact description.

Figure 1 is a side elevation showing one 10 form of sign structure to which my invention has been applied, and in which parts have been broken away.

Fig. 2 is a sectional plan view II—II of Fig. 1.

15 My invention relates to protectors for signs or lamps and more particularly to outside illuminated signs or lamps, having a supporting band or frame and glass plates surrounding an electric light bulb or other 20 suitable lighting means. The glass plates in devices of this character are frequently broken by boys throwing stones and invariably both glass plates and the electric light bulbs are broken simultaneously.

25 The object of my invention is to provide a protector which will prevent the simultaneously breaking of both glass plates and always protect the electric light bulb, and which protector is of such a character and 30 so positioned that it will not detract from the appearance of the lamp or sign structure.

The precise nature of my invention will 35 be best understood by reference to the accompanying drawings, which will now be described, it being premised, however, that various changes may be made in the detail of construction and general arrangement of the parts without departing from the spirit 40 and scope of my invention as defined in the appended claims.

Referring to the accompanying drawings, the reference character 2 designates a pedestal for supporting the lamp structure or 45 sign, which may be of any approved type. The lamp structure or sign comprises an annular metallic frame which is formed of the members 3 and 4, which members are secured to each other by means of a clenched 50 seam or joint as indicated at 5. 6 is a base member secured to the members 3 and 4,

which is provided with a suitable flange for securing the lamp structure to the pedestal or other support. The base member 6 is hollow for passing the same over an electric light bulb 7 which may be supported in any desired manner on the pedestal 2, or may be supported on the lamp structure direct. The members 3 and 4 are flanged at their edges for the reception of flanged rings 8, which form supports for glass plates 9. In the drawings these glass plates 9 are held in position within the flanged rings 8 by spring wire rings 10.

Mounted within the frame formed of the 65 members 3 and 4 is a wire mesh protector having a body member 11 which surrounds the electric light bulb, and wings 12 and 13 extending from the body member toward the inner surface of the supporting frame. 70 In the drawings these wings are secured to the joint between the two members 3 and 4, although it will readily be understood that the protector may be made of any desired material other than the wire mesh, and may 75 be secured within the frame in any desired manner between the glass plates 9. It will also be understood that the form of the protector may be varied in accordance with the requirements for the particular structure 80 in which it is to be placed.

The advantages of my invention result 85 from the provision of a protector within a supporting frame which is located between the glass plates mounted therein.

I claim:

1. A lamp or sign structure having a supporting frame, a glass plate mounted in each side of the frame, and a protector interposed between the glass plates and hidden thereby; 90 substantially as described.

2. A lamp or sign structure having a supporting frame, a glass plate mounted in each side of the frame, and an open mesh hidden protector interposed between the glass plates 95 and supported by the frame; substantially as described.

3. A sign structure having a supporting frame, a glass plate mounted in each side of the frame, and a protector interposed between the glass plates and supported by the frame, there being a space within the lamp 100

structure for an electric light bulb surrounded by the protector; substantially as described.

4. A lamp or sign structure having a supporting frame, means on each side of said frame for supporting a glass plate, a protector between the glass supporting means within the frame, said protector having a

body portion for incasing an electric light bulb, and wings extending from said body 10 portion toward the inner wall of the supporting frame, substantially as described.

In testimony whereof, I have hereunto set my hand.

JOHN L. DAWES.
